UNITED STATES PATENT OFFICE

108,071

DESIGN FOR A LANTERN CHIMNEY

Edwin J. Fraser, Chicago, Ill.

Application March 3, 1937, Serial No. 67,961

Term of patent 14 years

To all whom it may concern:

Be it known that I, Edwin J. Fraser, a citizen of the United States, residing at Chicago, in the county of Cook and State of Illinois, have invented a new, original, and ornamental Design for a Lantern Chimney, of which the following is a specification, reference being had to the accompanying drawing, forming part thereof.

Figure 1 is a perspective view of a lantern chimney showing my new design, and

Fig. 2 is a top plan view of the same.

My design is characterized by a relatively squat cylindriform hollow metallic body having parallel with its main axis a vertically extending

circular flange on each open end and circular flanges formed on the medial portion of the side wall of said body extending at right angles both to said axis and to each other, each of the latter flanges having a transparent conoidal lens seated therein, and the portion of the side walls adjacent said latter flanges when viewed from the top, as shown in Fig. 2, definitely protrude outwardly to merge with the base portions of said flanges.

I claim:

The ornamental design for a lantern chimney as shown and described.

EDWIN J. FRASER.
